UNITED STATES PATENT OFFICE.

FRANK W. DODGE, OF NEW HAVEN, CONNECTICUT, ASSIGNOR TO THE SEAMLESS RUBBER COMPANY, INC., OF NEW HAVEN, CONNECTICUT, A CORPORATION OF MASSACHUSETTS.

DESIGN FOR AN INFLATABLE DOLL OR SIMILAR ARTICLE.

61,387.

Specification for Design.

Patented Aug. 22, 1922.

Application filed April 1, 1922. Serial No. 1,480. Term of patent 14 years.

To all whom it may concern:

Be it known that I, FRANK W. DODGE, a citizen of the United States, of New Haven, in the county of New Haven and State of Connecticut, have invented a new, original, and ornamental Design for an Inflatable Doll or Similar Article, of which the following is a specification, reference being had to the accompanying drawing, forming part hereof.

The figure is a plan view of an inflatable doll, showing my new design.

I claim:

The ornamental design for an inflatable doll or similar article, substantially as shown.

Dated: March 25th 1922.

FRANK W. DODGE.
